United States Patent Office

Des. 202,356
Patented Sept. 21, 1965

202,356

TIE HOLDER OR SIMILAR ARTICLE

Kenneth K. Ozenghar, 3241 Mayfield,
La Crescenta, Calif.

Filed Dec. 21, 1964, Ser. No. 83,110

Term of patent 14 years

(Cl. D33—8)

FIG. 1.

FIG. 3.

FIG. 2.

FIG. 4.

FIG. 5.

FIGURE 1 is a perspective view of a tie holder or similar article, showing my new design.

I claim:

The ornamental design for a tie holder or similar article, substantially as shown.
